UNITED STATES PATENT OFFICE.

JOSEPH G. RAQUETTE, OF CLEVELAND, OHIO.

OUTLET-BOX.

1,230,218.

Specification of Letters Patent. Patented June 19, 1917.

Application filed December 10, 1915. Serial No. 66,130.

To all whom it may concern:

Be it known that I, JOSEPH G. RAQUETTE, citizen of the United States, residing at Cleveland, in the county of Cuyahoga and State of Ohio, have invented certain new and useful Improvements in Outlet-Boxes, of which the following is a specification.

This invention generally speaking relates to switch box structure and particularly that 10 class wherein each box is rectangular in configuration and is provided with removable sides arranged in a manner such that they may be removed and the remaining portion of the box secured to another box or box 15 portion in a gang.

More specifically the invention relates to a box comprising a main body portion whose ends and back are preferably in one piece, and whose sides which are removably secured to the main body portion by interlocking hooks and lugs, one of which, preferably the one at the back of the box, is secured to the main body portion by a screw or some other similar clamping means.

25 The invention may be further briefly summarized as consisting in the construction and combination of parts hereinafter set forth in the following drawings, description and claims.

30 Referring to the drawings, Figure 1 is a front elevation of a single box complete; Fig. 2 is a front elevation of a pair of boxes with their adjacent sides removed, said boxes being secured together in a gang; Fig. 3 is a horizontal section through the 35 center of the box shown in Fig. 1; Fig. 4 is a similar view of the two boxes shown in Fig. 2; Fig. 5 is a view in side elevation looking at one side of the box; and Fig. 6 is a similar view looking at the opposite side.

In the embodiment shown in the drawings, 1 represents the back of the box connected by inclined portions 2 with the ends 3 and 4. Each of the end portions 3 and 4 is provided 45 with an outwardly extending lug 5 utilized for supporting any device which may be supplied to the box, with screws 6 for receiving suitable box supporting ears 7, and with side engaging hooks 8 and 9, the former 50 extending in a plane in parallelism with the end but out of alinement with the end as shown in Fig. 1. The hook 9 is flat and is bent inward at right angles to the plane of the upper end of the box as shown in Fig. 1. The openings of the hooks 8 are toward the 55 rear of the box and the openings of the

hooks 9 are toward the front of the box. In other words the box body portion is provided with a flat hook 8 arranged in parallelism with the end to which it is secured 60 but formed out of its plane with its opening toward the rear and with a hook 9 bent up near the side edge of the end at right angles to the end with the opening of the hook toward the front of the box, similar 65 hooks of the two ends being arranged on the same side of the box body portion.

The back of the box is provided with a threaded opening 10, near the edge of the side having the hooks 8, for a screw 11, while 70 near the opposite edge is an opening 12 receiving loosely the shank of a screw 13. The metal of the back of the box near this opening 12 is extended to form two spaced ears 14 which are formed to the rear of the plane 75 of the back of the box and to the side of the box so that they will overhang the rear of the back of an adjacent box body portion and the opening between the ears will be in alinement with the opening 10 of such adjacent box body portion. This is clearly 80 shown in Fig. 4.

The box is provided with two sides 15 and 16 and since they differ in structure they 85 will be described separately.

The side 15 conforms to the configuration of the side of the body portion and is provided at its front corners with notches 17, which receive the shanks of the hooks 8 and 90 permit the end portions to extend over the outside face of this side plate. The back edge of this side plate 15 is provided with a pair of spaced lugs 18, shown in dotted lines in Fig. 1, and these extend at right 95 angles to the plane of the side and are adapted for engagement under the head of the screw 11 of the box body portion. It will be seen from the foregoing description of the side plate 15 that when the screw 11 is removed the side plate 15 may be applied 100 from the rear toward the front by extending it under the hooks 8, when the lugs 18 will engage the back of the box and may be clamped thereagainst by the screw 11.

The opposite side plate 16 of the box is 105 provided at its front corners with inwardly extending hooks 19 similar in all respects to the hooks 8, and these hooks 19 are adapted to interlock with the hooks 9 to secure the plate at its front corners, while the back 110 edge of the plate is provided with an inwardly extending lug 20 having a threaded

- opening therein for the reception of the threaded shank of the screw 13 extending through the opening 12. This screw when drawn up will clamp this side firmly in place. The side plate 15 may be removed by removing the screw 11 and sliding the plate to the rear, while the side plate 16 may be removed by withdrawing the screw 13 and pulling the plate out toward the front.
10. In connecting the boxes in a gang adjacent side plates are removed. The user removes the side plates from unlike sides of the box in which case the hooks of one will readily coöperate with the hooks of the other, securing the boxes at their front edges, and the lugs 14 at the rear will readily coöperate with the screw 11. Time can be saved in manipulating the boxes if the screw 11 is not entirely withdrawn, but 15 is merely loosened in the side plate, for when it is loosened the side plate may be swung outward at the back so that its lugs 18 clear the screw when the plate may be removed.
20. It is obvious from the foregoing that boxes may be joined in a gang very readily.
25. Having described my invention, I claim:—
1. An outlet box, comprising a body consisting of a back and two end members, said end members at one side having notched ears extending laterally therefrom beyond the side of the box in planes parallel therewith and spaced inwardly therefrom, and at their opposite sides being provided with notched ears bent inwardly at right angles to their planes, a side plate for the first named side of the box whose front edge enters the notches in said parallel ears and whose other edge has a recessed ear lying outside of the back of the box, a screw passing through the recess of said last named ear into a threaded opening in the back of the box, a side plate for the second named side of the box whose front edge is provided with notched ears entering the right angled ears of the body and whose opposite edge has an ear lying within the back of the box, and a screw passing through an opening in the back of the box and threaded into said last named ear.
2. An outlet box, comprising a body consisting of a back and two end members, said end members at one side having notched ears extending laterally therefrom beyond the side of the box in planes parallel therewith and spaced inwardly therefrom, and at their opposite sides being provided with notched ears bent inwardly at right angles to their planes, the back of said box at the second named side having a recessed ganging ear extending beyond the side of the box in a plane parallel with its back and spaced outwardly therefrom, a side plate for the first named side of the box whose front edge enters the notches in said parallel ears and whose other edge has a recessed ear lying outside of the back of the box, a screw passing through the recess of said last named ear into a threaded opening in the back of the box, a side plate for the second named side of the box whose front edge is provided with notched ears entering the right angled ears of the body and whose opposite edge has an ear lying within the back of the box, and a screw passing through an opening in the back of the box and threaded into said last named ear.
3. In an outlet box, a body consisting of a back and two end members, said end members at one side having notched ears extending laterally therefrom beyond the side of the box in planes parallel therewith and spaced inwardly therefrom, and at their opposite sides being provided with notched ears bent inwardly at right angles to their planes, the back of said box at the first named side being provided with a threaded opening and at the second named side with a plain opening and a recessed ganging ear extending beyond the side of the box in a plane parallel with its back and spaced outwardly therefrom.

In testimony whereof I affix my signature in presence of two witnesses.

JOSEPH G. RAQUETTE.
